CHILD'S GARMENT WITH INNER MOISTUREPROOF PANTS

Filed June 21, 1949

UNITED STATES PATENT OFFICE

2,522,421

CHILD'S GARMENT WITH INNER
MOISTUREPROOF PANTS

Charles Wolf, New York, N. Y., assignor to Famous Children's Wear, Inc., New York, N. Y., a corporation of New York

Application June 21, 1949, Serial No. 100,344

5 Claims.

(Cl. 2—80)

1

This invention relates to children's apparel, and more particularly to apparel of a type combining an outer garment with an inner garment.

It is an object of the present invention to provide a child's legged outer garment with an attached inner or under-garment of pants form which will under no circumstances become tangled in the outer garment, and which will be put on or taken off a child together with the outer garment.

It is another object of the present invention to make the under-garment in the form of spacious rompers, and to fashion the same and the outer garment and attach them to each other, in such a manner that the rompers will, without fail and without any assistance from an attendant, fit themselves to, and come off a child on merely putting the outer garment on, and taking it off, the child, respectively.

It is another object of the present invention to combine the outer garment and the inner rompers so that a child will, in wearing the rompers, experience no discomfort by reason of its attachment to the outer garment, and the outer garment will, when worn, neither suggest the attachment thereto of the inner rompers, nor become in any way dishevelled by the latter.

It is a further object of the present invention to make the attached rompers of moisture-proof material, and to provide for elastic closure of the leg ends thereof on, and their complete separation from, a child's legs on merely putting the outer garment on, and taking it off, the child, respectively.

The above and other objects, features and advantages of the present invention will be more fully understood from the following description considered in connection with the accompanying illustrative drawings.

In the drawings:

Fig. 1 is a perspective view of a child's garment embodying the present invention, the garment being shown closed for wear;

Fig. 2 is a similar perspective view of the same garment, shown opened;

Fig. 3 is a section taken on the line 3—3 of Fig. 2;

Fig. 4 is a section taken on the line 4—4 of Fig. 3, the section being taken as though the garment in Fig. 3 were shown complete instead of cut in half; and

Fig. 5 is an enlarged fragmentary section taken on the line 5—5 of Fig. 3.

Referring to the drawings, the reference numeral 10 designates a suit or dress for a child, comprising an outer garment 12 and an inner or under-garment 14. The outer garment 12 is, in the present instance, of a commonly used overall pattern for children, while the inner garment 14 is in the form of rompers. The overall-type outer garment 12 comprises a body 16 on which legs 18 and 20, respectively, are provided. The body 16 of the outer garment 12 is on opposite sides

2

thereof and approximately at hip-level provided with expansion flaps 22, respectively, which may be sewn to slitted portions 23, respectively, of the garment body 16 in the manner best shown in Fig. 3, and which serve to keep the top of the body 16 closed circumferentially. When the outer garment 12 is closed on top of the body 16 thereof (Figs. 1 and 2), the flaps 22 are folded inwardly of the garment, and the slitted portions 23 of the latter then simulate pocket openings. The legs 18 and 20 are on the inside parted at 24 and 26, respectively, throughout their longitudinal extent and also across the crotch 28 (Figs. 2 and 3). The legs 18 and 20 and also the crotch 28 of the outer garment are normally closed by any suitable means, such as companion male and female snap fastener elements 30 and 32, respectively. Suitably secured, as by stitches 34, to the top of the body 16 of the outer garment 12 at the front and back thereof are front and back flaps 36 and 38, respectively. For closing the top of the body 16 of the garment 12 around the child's waist, the adjacent ends of the front and back flaps 36 and 38, respectively, may conveniently be provided with companion snap fastener elements 42 and 44, respectively, which may be snapped closed on folding the adjacent expansion flaps 22 inwardly into the body 16. For the secure support of the outer garment 12 on a child, the back flap 38 thereof may be provided with shoulder straps 46 which are provided at their free ends with snap fastener elements 49 (Fig. 3), companion elements 50 of which are provided on the front flap 36 for the releasable attachment to the latter of the ends of the shoulder straps 46.

The inner or undergarment 14, being in this instance in the form of rompers, is of the customary baggy shape of the latter, and is in parts attached to the body 16 of the outer garment 12 so as to be held in place therein without, however, being interfered with by the latter in its characteristic function as rompers. The inner garment 14, is, in the present instance, made of any suitable moisture-proof plastic sheet material which may be fashioned in any suitable manner from individual pieces (not shown). In accordance with its instant use as rompers, the legs 52 and 54 of the inner garment 14 are at their open ends gathered as at 56 on elastic bands 58, respectively, so as resiliently to close on a child's legs when the garment is worn.

The inner garment 14 is at its top attached throughout its circumference to the adjacent top, including the slitted portions 23, of the body 16 of the outer garment 12 (Figs. 3 and 4), preferably by the same stitches 34 by means of which the front and back flaps 36 and 38 are secured to the body 16. The inner garment 14 is furthermore secured, by simple line stitching 55 and 57, for instance, to the central longitudinal portions 51 and 53, respectively, of the body 16 of the outer garment at the front and back thereof, respectively (Figs. 2 and 4). The legs 52 and 54

of the inner garment 14 are, like the legs 18 and 20 of the outer garment 12, parted as shown at 59 (Figs. 2 and 4) on the inside throughout their longitudinal extent and across the crotch 60. The parted sides 62, 64 and 66, 68 of the legs 52 and 54, respectively, are sewed or otherwise secured to the adjacent parted sides of the legs 18 and 20 of the outer garment 12 in the fashion shown in Figs. 2 and 4, so that the legs 52 and 54 of the inner garment 14 will close on a child's legs on closing the legs 18 and 20 of the outer garment 12 by means of the snap fastener elements 30 and 32. More particularly, the parted sides 62, 64 and 66, 68 of the legs 52 and 54, respectively, of the inner garment 14 extend into and are secured in stitched hems 70, 72 and 74, 76 on the adjacent parted sides of the legs 18 and 20, respectively, of the outer garment 12, and the male and female snap fastener elements 30 and 32, respectively, are secured to the respective hems 72, 76 and 70, 74 (Fig. 2). In order that the elastic bands 58 in the inner garment 14 will, on closure of the legs 52 and 54 thereof, compel the latter into resilient closing engagement with a child's legs, the bands 58 are sewed or otherwise secured with their ends to the adjacent parted sides of the legs of the outer garment 12 in the fashion shown in Figs. 2 and 4.

It will be understood from the preceding description that the inner garment 14 is, with the exception of its line attachment to the top, the central front and back portions and the parted sides of the legs, of the body 16 of the outer garment 12, unattached to the latter and is accordingly sufficiently free to allow the child freedom of motion unobstructed from the outer garment 12. It will be further noted from Fig. 4 that the inner garment 14 is throughout its top end contiguous with the adjacent top end of the body 16 of the outer garment 12, so that a child has no choice but to step correctly into the inner garment 14 when putting on the combination garment 10. Furthermore, the parted legs of the outer and inner garments 12 and 14, respectively, dispense with the usual cumbersome task of directing the child's legs into the correct legs of conventional overall-type garments and rompers, for the legs of the instant garments will not be formed or closed until after the garments are put on a child. After the garments are put on a child, as explained, the parted legs thereof are closed about the child's legs by the simple expediency of closing the snap fastener elements 30 and 32. The parted legs of the instant garments further permit an attendant readily to take the latter off a child, simply by pulling them over the child's head and raised arms.

While I have shown and described the preferred embodiment of my invention, it will be understood that various changes may be made in the present invention without departing from the underlying idea or principles of the invention within the scope of the appended claims.

Having thus described my invention, what I claim and desire to secure by Letters Patent is:

1. A child's combination garment, comprising an outer garment having a body-encircling portion, legs and a crotch at which said legs meet, the latter being on their adjacent sides parted throughout their longitudinal extent and across said crotch, and an inner garment having legs, a crotch at which the latter meet, and a body-encircling portion attached to that of said outer garment for wear beneath the latter, the legs of said inner garment being on their adjacent

sides parted throughout their longitudinal extent and across the crotch at which they meet, and the adjacent parted sides of the adjacent legs, respectively, of said inner and outer garments being attached to each other for simultaneous closure of said adjacent legs, respectively, and releasable fasteners on the parted sides of said adjacent legs, respectively, for closing the latter.

2. A child's combination garment as set forth in claim 1, in which said garment is in the form of rompers and further comprises elastic bands at the leg ends thereof, respectively, for causing the latter resiliently to engage a child's thighs, respectively, on closing said adjacent legs, respectively, of said outer and inner garments, and the body-encircling portion of the inner garment has a top-waist encircling part attached circumferentially to the body-encircling portion of said outer garment.

3. A child's combination garment, comprising an outer garment having a body-encircling portion and extending at least to a child's thighs when worn, an inner garment having a top waist-encircling portion attached circumferentially to the inside of said outer garment for wear of said inner garment beneath the latter, said inner garment further having legs and a crotch at which said legs meet, and the latter being on their adjacent sides parted throughout their longitudinal extent and across said crotch, and said inner garment being further attached between its top portion and crotch to central longitudinal portions of the front and back, respectively, of said outer garment, and releasable fasteners on said parted sides of said legs, respectively, for closing the latter.

4. A child's combination garment as set forth in claim 1, in which the inner garment is formed of waterproof material.

5. A child's combination garment, comprising an outer garment having a body-encircling portion, legs and a crotch at which said legs meet, the latter being on their adjacent sides parted throughout their longitudinal extent and across said crotch, and an inner waterproof garment having legs, a crotch at which the latter meet, and a body-encircling portion attached to that of said outer garment for wear beneath the latter, the legs of said inner garment being on their adjacent sides parted throughout their longitudinal extent and across the crotch at which they meet, and the adjacent parted sides of the adjacent legs, respectively, of said inner and outer garments being attached to each other for simultaneous closure of said adjacent legs, respectively, and releasable fasteners on the parted sides of said adjacent legs, respectively, for closing the latter, said inner garment having elastic circumferential portions at the leg ends thereof, respectively, for resiliently engaging a child's thighs therearound, on closing said adjacent legs, respectively, of said outer and inner garments.

CHARLES WOLF.
